US00D855217S

(12) **United States Design Patent** (10) Patent No.: **US D855,217 S**
(45) Date of Patent: **** Jul. 30, 2019**

(54) **MOLDED SURFACE OF A CONCRETE PRODUCT**

(71) Applicant: **Anchor Wall Systems, Inc.**,
Minnetonka, MN (US)

(72) Inventors: **Jimmie L. Mugge**, Inver Grove
Heights, MN (US); **Jay J. Johnson**,
Star Prairie, WI (US); **Robert Joel
Wolter**, Chaska, MN (US)

(73) Assignee: **Anchor Wall Systems, Inc.**,
Minnetonka, MN (US)

(**) Term: **15 Years**

(21) Appl. No.: **29/643,616**

(22) Filed: **Apr. 10, 2018**

Related U.S. Application Data

(62) Division of application No. 29/620,564, filed on Feb.
22, 2017, now Pat. No. Des. 820,473, which is a
division of application No. 29/505,387, filed on Oct.
6, 2015, now Pat. No. Des. 783,860, which is a
division of application No. 29/474,662, filed on Dec.
17, 2014, now Pat. No. Des. 743,054, which is a
division of application No. 29/463,927, filed on Apr.
8, 2014, now Pat. No. Des. 722,391, which is a
division of application No. 29/442,955, filed on Jun.
18, 2013, now Pat. No. Des. 705,951, which is a
division of application No. 29/442,007, filed on Nov.

CLAIM

The ornamental design for a molded surface of a concrete product, as shown and described.

DESCRIPTION

FIG. 1 is a perspective view of a molded surface of a concrete product, according to our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawing views are included for the purpose of illustrating portions of the molded surface of a concrete product that form no part of the claimed design.

1 Claim, 7 Drawing Sheets

Related U.S. Application Data

9, 2012, now Pat. No. Des. 687,167, which is a division of application No. 29/395,232, filed on Dec. 20, 2011, now Pat. No. Des. 673,693, which is a division of application No. 29/372,509, filed on Nov. 29, 2010, now Pat. No. Des. 653,772.
